ATTORNEY

UNITED STATES PATENT OFFICE.

HANS SATTLER, OF SHEBOYGAN, WISCONSIN.

VIBRATION-RECORDER.

1,309,813.

Specification of Letters Patent. Patented July 15, 1919.

Application filed October 2, 1918. Serial No. 256,614.

To all whom it may concern:

Be it known that I, HANS SATTLER, a citizen of the United States, and resident of Sheboygan, in the county of Sheboygan and 5 State of Wisconsin, have invented certain new and useful Improvements in Vibration-Recorders; and I do hereby declare that the following is a full, clear, and exact description thereof.

10 My invention relates to new and useful improvements in vibration recorders, more particularly of the general type disclosed in Patent No. 1,240,883 granted to me September 25, 1917, such type of recorder including a clock-work mechanism for driving a record receiving dial which is engageable by a pendulum controlled stylus, whereby to automatically record the vibration set up incidental to the running of automobiles or 15 other vehicles, and to thus afford a positive indication of the amount of running time of the vehicle within a certain period, and general conditions of speed and roughness of travel to which the vehicle is subjected.

20 25 It is in general the object of my invention to simplify and otherwise improve the structure of recorder devices of this character, with a view to increasing the durability of such devices in continued use, and with a 30 view to increasing the recording efficiency of such devices.

As in my said patent, I contemplate the use of a conventional clock mechanism for driving the record dial, and it is more particularly an object of my invention to provide an improved mounting for the clock mechanism whereby it may be most readily associated with a record dial, and whereby to avoid the setting up of undue stress in 40 the clock mechanism incidental to its association with the recording dial.

A further object resides in the provision of an exceedingly compact arrangement of the various parts as heretofore mentioned, 45 whereby the parts may be inclosed in a casing to protect the parts and prevent interference with their desired functions.

With the above and other objects and advantages in view, which will be apparent as 50 the description proceeds, my invention, resides in the novel features of construction, combination and arrangements of parts as hereinafter described and defined by the appended claims.

55 In the accompanying drawings:
Figure 1 is an elevational view of the cas-

ing of my improved vibration recorder, the door of said casing being swung open, and the recording mechanism being shown in the casing in section, as indicated by the 60 line 1—1 of Fig. 2.

Fig. 2 is a sectional view through the mechanism and casing with the door closed, on the broken line 2—2 of Fig. 1.

Referring now more particularly to the 65 drawings, there is provided a casing including a back wall 5 and a peripheral wall 6 to one side of which is hinged a door 7, forming the front wall of the casing. The back wall carries a pair of hook lugs 8 at its 70 upper portion engageable over any desired support member on the vehicle, and the lower portion of the back wall is provided with an apertured inwardly extending boss 8^a for the reception of a screw to be engaged 75 in the support member over which the hook lugs 8 are engaged, whereby to lock the casing against detachment. Since communication with the interior of the casing is controlled by the door 7 which would be provided with conventional lock mechanism 80 (not shown), removal of the casing without proper authority is impossible.

A carrying plate 9 is secured eccentrically in the casing by screws 10 passed through 85 its peripheral portion and engaged in a set of, in the present instance, three studs 11 projecting inwardly from the back wall 5 of the casing, the plate being thus held parallel with and spaced from the casing. 90 This plate is apertured for the reception of the usual attaching screws 12 projecting from one of the assembled side plates 13 of a conventional clock mechanism unit. This clock mechanism includes the main spring 95 14 mounted on a shaft 15, and the clock mechanism and its carrying plate 9 are so disposed relative to the casing that the main spring shaft 15 is disposed axially in the casing and consequently adjacent one side 100 of the carrying plate. A sleeve 16 projects forwardly from the carrying plate axially of the casing, and in carrying out my invention I secure a gear wheel 17 on the main spring shaft of the clock mechanism, this 105 gear wheel carrying a squared winding stud 17 which extends into the sleeve 16 for engagement by any suitable winding key insertible in the sleeve. The plate 9, inwardly of the sleeve 16 has a portion offset to form 110 a well 18 open at the side of the plate adjacent the clock mechanism, and projecting

into this well is a pin 19 carried by the offset portion of the plate and on which is mounted a gear wheel 20 which meshes with the gear wheel 17 of the winding shaft 15 and 5 which is rigidly connected with a pinion 21 disposed in the well and projecting at the forward side of the plate 9 through a cut-away portion of the well. This pinion meshes with a series of gear teeth 22 carried 10 on a journal sleeve 23 which is mounted on the sleeve 16. The intermediate portion of the sleeve 23 carries a seating plate 24 for the indicator dial structure, later to be described.

15 By the foregoing construction, a conventional clock mechanism may be associated with a record dial for driving the same, in a most economical manner, and in a manner avoiding the imposition of any unusual 10 stresses upon the clock mechanism which might interfere with its accurate continued operation. It is noted that the clock mechanism is carried entirely by the plate 9, which also carries the recording dial plate 24 in an 20 independent manner. The clock mechanism is thus mounted in a manner practically identical to its mounting in an ordinary clock casing, and the operative conditions for which it is conventionally designed are 25 thus retained. The only modification of the clock mechanism is the attachment of the gear 17 to its winding shaft.

In the present arrangement, for procuring the record, a sheet of carbon or similar paper 35 25 is placed against the seating plate 24 and the record disk 26 is placed against this carbon sheet, both sheets being held against rotation on the plate by a spur 27' projecting forwardly from a peripheral portion of the 40 plate. The record sheet is supported by a backing plate 27 which is secured against the plate by a collar 28 engageable on the outer end of the journal sleeve 23 and provided with locking pins 29 of conventional 45 nature engageable in slots of the journal sleeve for procuring a quick detachable connection. It may be noted at this point that the journal sleeve is held assembled on the sleeve 16 by a nut 30 threaded on the forwardly projected end of the sleeve 16 and bearing against the end of the journal sleeve, and this nut is of lesser diameter 50 than the journal sleeve whereby to permit detachment of the collar 28 and backing plate for ready removal and replacement 55 of record sheets 26.

For marking the record sheet, an angular pendulum lever is pivoted at its angle in the bifurcated end of a bearing bracket 31 60 secured to the upper portion of one side of the back wall 5, this lever including a vertically depending weight arm 32 and a relatively short inwardly inclined arm 33 carrying a transverse head 34 in which is disposed a stylus 35 engaging the carbon sheet

25, this stylus being preferably yieldably urged to project from said head in the manner of my said previous patent, although no specific mounting of the stylus is shown.

Thus, travel to which a vehicle carrying 70 the recording device is subjected, will set up continuous oscillations of the pendulum lever by reason of the vibration of the vehicle part to which the recording device is attached, and the speed and roughness of 75 travel to which the vehicle is subjected will be indicated by the magnitude of the vibrations, as recorded on the record sheet 26 by the stylus 35.

Thus an accurate record may be obtained 80 of the conditions to which a vehicle is subjected in a given period of time, and my device is preferably so arranged as to procure a single rotation of the record sheet in a twenty-four hour period, it being noted that 85 a reduced train of gears formed by the various gears and pinions heretofore specifically described, is interposed between the winding shaft 15 of the clock mechanism and the gear teeth of the journal collar to effect this 90 operation.

To limit the oscillatory movements of the weight arm 32, a pair of studs 36 project inwardly from the back plate 5 at the sides of said weight arm, and inasmuch as the 95 casing may be tilted to one side or the other in its attachment on a vehicle, it is desirable to provide a horizontal adjustment for these studs whereby the proper oscillatory play of the weight arm may be determined under 100 such conditions. To this end, the studs 36 are mounted on a bracket plate 37 which is provided with a horizontal adjusting slot 38 through which are passed screws 39 105 clamping the plate to the back wall 5.

The peripheral wall of the casing is provided at substantially its central portion with an annular inwardly extending partition flange 40 which projects inwardly to a point adjacent the periphery of the seating 110 plate 24, this flange being preferably integral with the peripheral wall of the casing, which in turn is integral with the back wall, thus providing an exceedingly solid and simple casing structure. This partition 115 flange is provided with a transverse slot 41 receiving the stylus head of the pendulum lever, and the lower portion of the flange is apertured at 42 to permit insertion of the securing screw of the casing in the boss 8 of 120 the back wall.

What is claimed is:

1. A vibration recorder including a main support, studs projecting from said main support, a carrying plate mounted on said studs, a journal member projecting outwardly from the carrying plate, a record member mounted on said journal member, a clock mechanism assembly unit secured to said plate between the plate and support, a 125

- drive connection between said clock mechanism unit and record member, and a vibratory stylus carried by the main support and engaging the record member.
5. A vibration recorder including a main support, studs projecting from said main support, a carrying plate mounted on said studs, a journal projecting outwardly from the carrying plate, a clock mechanism assembly unit disposed between the carrying plate and main support, a record member mounted on the journal, a drive connection between the record member and the clock mechanism, and a vibratory stylus carried by the main support and engageable with the record member.
10. A vibration recorder including a main support, studs projecting from said main support, a carrying plate mounted on said studs, a journal projecting outwardly from the carrying plate, a clock mechanism assembly unit disposed between the carrying plate and main support, and including mounting screws projecting from one of its side plates and secured in said carrying plate, a record member mounted on the journal, a drive connection between the record member and the clock mechanism, and a vibratory stylus carried by the main support and engageable with the record member.
15. A vibration recorder including a main support, studs projecting from said main support, a carrying plate mounted on said studs, a journal projecting outwardly from the carrying plate, a clock mechanism assembly unit disposed between the carrying plate and main support, and including a winding shaft, means independent of
- the clock mechanism unit for securing the carrying member to the main support, a journal sleeve on the carrying member in alignment with the winding shaft to permit access to the shaft through the sleeve, a record member on the journal sleeve, a reducing train of gears connecting the winding shaft and the record member, and a vibratory stylus carried by the main support and engageable with the record member.
20. A vibration recorder including a main support, studs projecting from said main support, a carrying plate mounted on said studs, a journal projecting outwardly from the carrying plate, a clock mechanism assembly unit disposed between the carrying plate and main support, and including a portion of the carrying plate being outwardly offset to form a well, said well being cut-away at one side, a pin carried by said offset portion of the plate and projecting into the well, a gear on the record member, a gear journaled on the pin and meshing with the gear of the record member, a drive connection between said pin journaled gear and the clock mechanism, and a vibratory stylus carried by the main support and engageable with the record member.
25. A vibration recorder including a main support, a carrying member, a clock mechanism assembly unit disposed between the carrying member and main support and including a winding shaft, means independent of
30. A vibration recorder including a main support, a carrying member, a clock mechanism assembly unit disposed between the carrying member and main support and including a winding shaft, means independent of
35. A vibration recorder including a main support, a carrying member, a clock mechanism assembly unit disposed between the carrying member and main support and including a winding shaft, means independent of

In testimony that I claim the foregoing 65
I have hereunto set my hand at Sheboygan,
in the county of Sheboygan and State of
Wisconsin.

HANS SATTLER.
